CUFF LINK CONSTRUCTION

Ingemar Taegtstroem, New York, N. Y., assignor
to Jacques Kreisler Manufacturing Corpora-
tion, North Bergen, N. J., a corporation

Application April 15, 1948, Serial No. 21,193

4 Claims. (Cl. 24—97)

1

This invention relates to cuff links, and more especially to cuff links of the type having opposite ends or shields on a rigid connecting shank of which at least one shield is hinged on the shank.

It is the primary object of the present invention to provide a cuff link of this type which is of exceptionally strong construction, and of which the exposed shields and shank may nevertheless be formed solely with a view toward lending to the cuff link a pleasing appearance without giving regard to its strength of construction.

It is another important object of the present invention to provide a cuff link of this type of which the hinged shield may snap into certain preassigned angular dispositions on the shank by a spring action which assuredly will remain strong and positive over a long period of time.

It is another important object of the present invention to form the shank of the cuff link as a convenient receptacle for a relatively strong spring that lends to the hinged shield its strong snap action into the several angular dispositions on the shank.

It is another important object of the present invention to provide a cuff link of this type which consists of a few simple parts that may readily be assembled in a fashion requiring hardly any skill.

The above and other objects, features and advantages of the present invention will be more fully understood from the following description considered in connection with the accompanying illustrative drawings.

In the drawings:

Fig. 1 is a front elevation, drawn at an enlarged scale, of a cuff link embodying the present invention;

Fig. 2 is a side elevation of the same cuff link;

Fig. 3 is a section through the cuff link as taken on the line 3—3 of Fig. 1;

Fig. 4 is a section through the cuff link as taken on the line 4—4 of Fig. 2; and

Fig. 5 is a section through the cuff link as taken on the line 5—5 of Fig. 3.

Referring to the drawings, the reference numeral 10 designates a cuff link of the type having opposite ends or shields 12 and a rigid connecting stem or shank 14. As customary in cuff links of this type, one of the shields, in the present instance the shield 12', is hingedly mounted on the adjacent end of the shank 14 so that the shield may be tilted from the disposition shown in Figs. 1 and 4 against either side of the shank 14, and vice-versa. The shank 14 of the cuff link is, in the present instance, formed

2

of several parts of which the outermost exposed part is in the form of a tubular sleeve 16 of generally ablong cross section (Fig. 5). Fittingly received in the sleeve 16 is an anchor member 18 which is generally U-shaped, being provided with spaced legs 20 and a connecting end or yoke 22. The sleeve 16 is, in the present instance, curved in side elevation (Figs. 2 and 3), and the spaced legs 20 of the anchor member are accordingly curved and in engagement with the most widely spaced wall portions 26 of the sleeve 16 (Figs. 3 and 5). The anchor member 18 may be provided with opposite lugs 28 that register with notches 29, respectively, in the adjacent end of the sleeve 16 (Fig. 3). The anchor member 18 may be press-fitted into the sleeve 16, and may additionally be secured therein in any suitable manner, as by soldering, for instance. The non-hinged shield 12" may be secured to the adjacent end of the shank 14 in any suitable manner. In the present instance, the shield 12" is shown provided with a tubular extension 30 that may fit over the adjacent end of the shank 14 and be permanently secured thereto, as by soldering, for instance.

As previously stated, the other shield 12' is hingedly connected to the adjacent end of the shank 14 of the cuff link. To this end, the shield 12' is provided with a rearwardly extending lug 34 through which extends a pivot pin 36 that is anchored with its ends in apertures 38 in the ends 40 of the legs 20. The apertured ends 40 of the legs 20 project to the outside of the sleeve 16 and straddle the lug 34 on the shield 12', as shown in Fig. 3. In the present instance, the apertures 38 in the leg ends 40 are in the form of elongated slots. The pivot pin 36 is held against axial movement in any suitable manner, as by heading the ends thereof as shown at 42.

Located in the sleeve 16 between the opposite legs 20 of the anchor member 18, and bearing with its ends against the yoke 22 of the anchor member and the lug 34 on the shield 12', respectively, is a compression spring 44 which is preferably of the wire type illustrated in Figs. 3 and 4. Thus the instant spring 44 is formed to resemble a W, of which the outer legs 46 bear against the yoke 22 and the shield lug 34, respectively. The spring 44 is so precompressed that its "latch" end 46 bears with considerable force against the adjacent lug 34 on the hinged shield 12'. The lug 34 on the shield 12' is provided with spaced indentations or notches 50 which are adapted for releasable interlock with the adjacent latch end 46 of the spring in the before-

mentioned angular dispositions of the shield 12' on the shank 14. In the instant construction of the cuff link, substantially the entire compression of the spring 44 is taken up by the hingedly connected anchor member 18 and shield lug 34, leaving the shank sleeve 16 as well as both shields 12 free from any strain in consequence of the compression of the spring 44. Hence, the exposed shank sleeve 16 and shields 12 may be constructed solely with a view toward lending to the cuff link a pleasing appearance, and without having regard to the strength of the construction of the cuff link. The instant provision of housing the spring in the shank of the cuff link also permits the use of a relatively large and strong spring 44 which may be made to exert a considerable yielding force against the shield lug 34 without noticeably tiring over a long period of use, wherefore the pivoted shield 12' will always be locked firmly, though releasably, in any one of its preassigned angular dispositions on the shank 14. The preferred formation of the spring 44 into W-shape and its specific location in the anchor member 18 may serve the additional purpose of increasing the compression of the spring by depressing the same to the extent where the apex 56 of the inner legs 58 of the spring is forced against the adjacent leg 20 of the anchor member, whereby the spring is divided at the apex 56 into separately compressible sections. The aggregate of the compression of these sections is, of course, considerably greater than the compression of the same spring if the same were, on compression, deflected the same amount without, however, being forced with its apex 56 against the adjacent leg 20 of the anchor member.

While I have shown and described the preferred embodiments of my invention, it will be understood that various changes may be made in the present invention without departing from the underlying idea or principles of the invention within the scope of the appended claims.

Having thus described my invention, what I claim and desire to secure by Letters Patent, is:

1. In a cuff link, the combination of a tubular shank of generally oblong cross section, a U-shaped member in said shank, said member having spaced legs and a connecting end portion, said legs extending longitudinally of said shank in engagement with the most widely spaced opposite wall portions thereof, and projecting with their ends to the outside of said shank, a shield having a portion hingedly mounted on said projecting leg ends, and a compressed spring in said shank between said legs and interposed between

said connecting end portion and shield portion, the latter being provided with spaced indentations adapted releasably to interlock with said spring in different angular dispositions of said shield on said member.

2. The combination in a cuff link as set forth in claim 1, in which said projecting leg ends are apertured, and said shield portion is also apertured and straddled by said projecting leg ends, and a pin extends through the aligned apertures in said leg ends and shield portion for the hinged mounting of said shield on said leg ends.

3. In a cuff link, the combination of a tubular shank of generally oblong cross section, a U-shaped member in said shank, said member having spaced legs with apertured ends and a connecting end portion, said legs extending longitudinally of said shank in engagement with the most widely spaced opposite wall portions thereof, and projecting with their apertured ends to the outside of said shank, a shield having a projecting apertured lug extending longitudinally between said projecting leg ends, a pin extending through the aligned apertures of said leg ends and shield lug for pivotally mounting the latter on the former, and a flat endwise compressed wire spring extending in said shank in zig-zag fashion between said legs and resiliently engaging with its opposite ends said connecting end portion and shield lug, respectively, said shield lug being provided with spaced indentations adapted releasably to interlock with the adjacent spring end in different angular dispositions of said shield on said member.

4. The combination in a cuff link as set forth in claim 3, in which said member is substantially of the same thickness as the wire of the spring, said spring is W-shaped and confined in said member by the most-narrowly spaced opposite wall portions of said shank, and the outer legs of said spring bear uniformly against said connecting end portion and shield lug, respectively, and the indentations in said shield lug extend longitudinally of the latter.
